PRINTING PLATE BASE

Horace W. Hacker, La Grange, Ill.

Application December 28, 1934, Serial No. 759,571

9 Claims. (Cl. 101—382)

My invention relates to lumber from which printing plate bases are to be cut to desired sizes and has for its purpose to so construct such lumber that bases cut therefrom will retain 5 their original form and size under conditions incident to their use.

In the drawings chosen to illustrate my invention the scope whereof is set forth in the appended claims:

10 Figure 1 is a fragmentary perspective view of a printing plate base cut from lumber constructed in accordance with my invention; and Figures 2, 3 and 4 are similar views of alternative forms of my invention.

15 Referring to Figure 1 my improved lumber is shown as having its top and bottom formed of sheets of nail penetrable and planeable material, in this instance sheets of cast metal 10 and 11. In casting these sheets I provide their 20 inner faces with cross tongues 12, although any other suitable type of formations may be provided on the inner faces of the sheets. Between these sheets I provide a plurality of wood blocks 13 having their cross grain ends disposed in parallel planes with the ends common to one 25 of the planes covered by the sheet 10 and the ends common to the other plane covered by the sheet 11. The cross grain ends of each of the blocks 13 are provided with cross grooves 14 which receive the cross tongues 12 of the sheets 10 and 11. The position of the cross tongues 12 and cross grooves 14 is such that, when the lumber is assembled as shown in Figure 1, they 30 serve to both interconnect the blocks 13 and also position them with their opposed faces spaced apart to avoid the possibility of any undesirable cumulative effect on the stability 35 of the lumber due to side swelling of the blocks. In assembling the lumber the sheets 10 and 11 and the cross grain ends of the blocks 13 are of course cemented together.

40 In the form of my invention shown in Figure 2 the inner faces of the sheets 10 and 11 are provided with cross knurling which produces somewhat pointed formations 15. In assembling this structure the parts are positioned in proper relation with cement applied between the blocks and sheets and then pressed together to force the formations 15 into the cross grain ends of 45 the blocks 13 as clearly shown in the drawings.

50 The structures shown in Figures 1 and 2 are characterized by the rigidity and strength essential to properly sustain the pressure incident to locking up a printing form in which either is embodied and also render possible the practical

use of wood with upright grain by preventing splitting of the wood blocks when nailed near an edge or corner due to the holding influence of the sheet 10 or sheet 11, according to which sheet is penetrated in nailing. The structure 5 shown in Figure 2 is also characterized by economy in production.

In the form of my invention shown in Figure 3 the construction and arrangement and relation of the blocks 13 is the same as that described in connection with Figures 1 and 2, but the sheets 10 and 11 are dispensed with and open grids 16 and 17 are engaged and cemented in the grooves 14.

The form of my invention shown in Figure 4 is similar in all respects to that shown in Figure 3, but embodies in addition sheets of nail penetrable and planeable material 18 and 19 cemented to opposite cross grain ends of the blocks 13 respectively and to related open 20 grids 16 and 17. In this instance the sheets 18 and 19 are shown as constituted of wood veneer, but said sheets may be made from any other suitable material. In this form of my invention planning for height can be accomplished with 25 greater facility than in the form shown in Figure 3.

In all the forms illustrated and described 30 distinct advantage is gained with respect to stability of height of the base as wood changes its dimensions very slightly in the direction of 35 the grain, while the spacing apart of opposed faces of the blocks serves to eliminate any cumulative effect on stability of form due to side swelling of the blocks.

35 While I have shown the blocks 13 in all the forms arranged with their grain upright it will be understood that other arrangements of the blocks can be resorted to without departing from the spirit of my invention or the scope of the 40 appended claims.

I claim:

1. Lumber from which printing plate bases are to be cut comprising sheets of nail penetrable and planeable material constituting the 45 top and bottom of the lumber, a plurality of wood blocks between the sheets said blocks having their opposed faces in spaced relation, and formations on at least one of the sheets engaged in the blocks.

50 2. Lumber from which printing plate bases are to be cut comprising a plurality of wood blocks positioned with opposite ends disposed in parallel planes respectively and with spaces between their adjacent opposed faces, and separate 55

block interconnecting means, one of which is engaged in the ends of the blocks common to one plane and the other of which is engaged in the ends of the blocks common to the other plane, both of said means being located entirely outside the spaces between adjacent opposed faces of the blocks.

3. Lumber from which printing plate bases are to be cut comprising a plurality of wood blocks positioned with opposite ends disposed in parallel planes respectively and with spaces between their adjacent opposed faces, and block interconnecting means engaged in the ends of the blocks common to one of said planes, said means being located entirely outside the spaces between adjacent opposed faces of the blocks.

4. Lumber from which printing plate bases are to be cut comprising sheets of nail penetrable and planeable material constituting the top and bottom of the lumber, a plurality of wood blocks between the sheets relatively positioned to provide spaces between their adjacent opposed faces, and formations on at least one of the sheets engaged in the blocks and disposed entirely outside said spaces.

5. Lumber from which printing plate bases are to be cut comprising sheets of nail penetrable and planeable material constituting the top and bottom of the lumber, a plurality of wood blocks between the sheets relatively positioned to provide spaces between their adjacent opposed faces and each of said blocks having its cross grain ends abutting the sheets respectively, and formations on at least one of the sheets engaged in the blocks and disposed entirely outside said spaces.

6. Lumber from which printing plate bases are to be cut comprising a plurality of wood blocks positioned with opposite ends disposed in parallel planes respectively and with spaces between their adjacent opposed faces, and open grids, one of which is engaged in recesses in the ends of the blocks common to one of the planes and the other of said grids being engaged in

recesses in the ends of the blocks common to the other plane, both of said grids being located entirely outside the spaces between adjacent opposed faces of the blocks.

7. Lumber from which printing plate bases are to be cut comprising a plurality of wood blocks positioned with opposite ends disposed in parallel planes respectively and with spaces between their adjacent opposed faces, an open grid engaged in recesses in the ends of the blocks common to one of the planes with said grid disposed entirely outside the spaces between adjacent opposed faces of the blocks, and sheets of nail penetrable and planeable material, one of which is secured to and covers the ends of the blocks common to one plane and the other of which is secured to and covers the ends of the blocks common to the other plane.

8. Lumber from which printing plate bases are to be cut comprising a plurality of wood blocks positioned with opposite ends disposed in parallel planes respectively and with spaces between their adjacent opposed faces, open grids respectively engaged in recesses in the ends of the blocks common to said planes with said grids disposed entirely outside the spaces between adjacent opposed faces of the blocks, and sheets of nail penetrable and planeable material, one of which is secured to the ends of the blocks common to one plane and the other of which is secured to and covers the ends of the blocks common to the other plane.

9. Lumber from which printing plates are to be cut comprising a plurality of wood blocks positioned with opposite ends disposed in parallel planes respectively and with each pair of their adjacent faces having an uninterrupted free space therebetween throughout their entire areas, and sheets of nail penetrable material, one of which is secured to and covers the ends of the blocks common to one plane and the other of which is secured to and covers the ends of the blocks common to the other plane.

HORACE W. HACKER.
